VACUUM TUBE

Warren G. Taylor, Chicago, Ill.

Application July 9, 1936, Serial No. 89,781

9 Claims. (Cl. 250—27.5)

This invention relates to vacuum tubes and particularly to vacuum tubes for use at extremely high frequencies and high potentials. Tubes under such conditions are used in short wave 5 radio and also in diathermy and for surgical operations with the so called electric knife. In the latter instance the tubes are subjected to unusually hard usage, ranging from a zero load up to a short circuit. The potentials and frequency used 10 on the tubes are such that the customary tube has had in many instances a short life.

It is an object of this invention to devise a tube construction in which extremely high frequencies will not result in high losses in the glass of the 15 tube and in which high potentials under such conditions will not result in damage to the tube. An additional object is to devise a heavy duty tube construction wherein the supporting frame work for the electrodes is electrically neutral and wherein no great differences of potential are impressed directly through the walls of the glass. Other objects will become apparent as the description proceeds.

Referring to the drawing:

Figure 1 shows an elevation of a tube embodying this construction with certain portions broken away.

Figure 2 is a section on line 2—2 of Figure 1. Figure 3 is a section on line 3—3 of Figure 2.

The tube comprises a glass bulb 1 having a re-entrant stem 2 coming up from the bottom and a smaller reentrant stem 3 coming down from the top of the tube. The entire electrode construction is supported around stem 2 by means of a wide metal band 5 clamped by a bolt 6 in the usual fashion. Carried by band 5 are four spaced upright metal rods 7 to 10 inclusive which run well up toward the top of the tube. Threaded through these four rods and disposed above stem 2 is an insulator 12 here shown as circular but which may be of any desired shape. The free ends of rods 7 to 10 inclusive are threaded through another insulator 13 similar to 12. The entire electrode structure is assembled between these two insulators 12 and 13 and together with these insulators forms a rigid construction removable as a unit from the tube.

Between insulators 12 and 13 an anode 15 is provided of any shape whatsoever. As shown here the anode is preferably of carbon having an elongated interior chamber 16 and a pair of wings 17 and 18 extending from the opposite sides thereof. Wings 17 and 18 are apertured and through these pass supporting rods 20 and 21, these rods 55 passing through suitable apertures in insulators

12 and 13. It will be noted that due to the location of wings 17 and 18 from the center of each anode wall that both rods 20 and 21 are spaced from the four rods 7 to 10 inclusive. Disposed around rods 20 and 21 are sleeves 22 to 25 inclusive. These sleeves extend from the inside insulator surface to the anode ends and serve to maintain the anode in a fixed vertical position as seen in Figure 1. Rods 20 and 21 have their bottom ends 26 and 27 distorted for locking purposes. 10

Rods 20 and 21 are bent inwardly at the top at 28 and 29 and terminate in a strap 30 disposed around small press 3. A lead 31 is sealed in small stem 3 and is welded to rod 21. Lead 31 has a metal cap 32 on the outside of the tube connected thereto to which the anode supply may be connected.

Disposed within anode 15 is a grid 35 of the usual wire construction wound around grid posts 36 and 37. These grid posts may project into apertures 38 and 39 in tube insulator 13 and at the bottom pass through similar apertures 40 and 41 in the bottom insulator 12. The bottom ends of grid post 36 and 37 extending below insulator 12 are preferably joined by a wire 42 from which 20 extends a lead 43. This lead is sealed in the bottom of press 2 at 44 and passes therethrough. 25

Within grid 35 a filamentary cathode 48 is provided. This cathode is bent into the shape of an M and has its ends joined to a pair of heavy wires 49 and 50 tightly pressed through apertures 52 and 53 in bottom insulator 12. The free ends 49 and 50 of the filament are joined to leads 55 and 56 sealed in press 2. 30

The bottom bight 57 of the filament is retained 35 by a hook 58 carried by a looped spring 59 anchored in the center of insulator 12. The top bights 60 and 61 of the filament are maintained taut by hooks 62 and 63 passing through top insulator 13 and tensioned by coil springs 64 and 65. 40 It is clear that the electrode assembly comprising the insulators 12 and 13 with posts 20 and 21 together with the grid and filament may be assembled and inserted into the tube as a unit. The four posts 7 to 10 inclusive are threaded through 45 the two insulators and thereafter crossbars 67 and 68 are welded to rods 7 and 10 and 8 and 9 respectively. This makes the skeleton frame work more rigid and anchors the assembly.

After the electrode assembly has been positioned 50 in the tube, upper strap 30 is adjusted over upper press 3. The rods 20 and 21 may be moved downwardly so that strap 30 may be disposed just below the tip of press 3, it being understood, of course, that lead 31 is straight at this time, and 55

then the strap may be pulled upwardly until the bumps 26 and 27 on the bottoms of these rods limit them. The cathode grid connections may then be made at the bottom and the anode connection may be made at the top as shown.

It is evident that strap 5 and the four rods 7 to 10 inclusive are not directly connected to any electrode and hence are at no definite potential with respect to the electrodes. The strap which 10 has been customarily at the anode potential but which in this instance is at no definite potential has no tendency to set up electrostatic strains through the glass wall of press 2. By providing the grid lead as shown through the side of the 15 bottom of press 2 it is clear that the electrostatic strain due to the grid cathode potential is distributed over a large glass surface. It is understood, of course, that the wires coming from the seal and exposed to the atmosphere may be insulated 20 in any suitable manner, such as by glass tubes or the like.

By providing the anode lead at the top of the tube the greatest difference in potential is impressed across the entire bulb.

25 A construction of this character has been found to be very sturdy mechanically and electrically and has successfully been operated under conditions where the usual construction frequently broke down. It must be remembered that the 30 insulating qualities of glass diminish very rapidly with increase in temperature. In the ordinary construction considerable di-electric losses at extremely high frequencies in glass tend to generate heat therein at the press where the 35 strap is located. When a tube of this type is overloaded, the increase in heat at the press reduced the insulating qualities of the glass, causing more losses and resulting in a direct puncture. With this construction even an extreme 40 overload has no appreciable effect.

What is claimed is:

1. A vacuum tube comprising an evacuated bulb having a reentrant stem at the two ends thereof, a metal strap disposed around each stem, 45 a plurality of rods extending from each stem toward the other stem, said rods being mechanically and electrically distinct from each other with the rods from the lower strap being electrically neutral to all tube electrodes, a pair of 50 insulating discs threaded through the rods from the lower strap, an anode supported by said rods from said upper stem, said anode being supported between said insulators, a grid and filamentary cathode supported by said insulating 55 discs within said anode, and connections sealed in said bottom stem for said cathode and grid.

2. The structure of claim 1 wherein said grid connection passes through the bottom of said bottom stem and wherein said filament connections pass through the free end of said bottom stem.

3. In an electron discharge device, an evacuated bulb having a reentrant stem terminating in a press at one end thereof, a metal strap disposed around said stem, a plurality of metal supporting rods carried by said strap and forming a framework extending toward the other end of said bulb, an electrode assembly insulatingly supported by said framework, said assembly comprising a pair of spaced insulators threaded over the wires of said framework and being the only elements of the entire electrode assembly touched by said framework, an anode supported between said insulators, a grid disposed within said anode 70 and supported between said insulators, a cathode 75

disposed within said grid and supported between said insulators, cathode leads sealed in said press and connected to the cathode terminals, a lead sealed in the stem remote from said press, another lead sealed in said bulb remote from both 5 stem and press, and electrically separate connections between said grid and anode to said two leads.

4. In an electron discharge device, an evacuated bulb having a reentrant stem terminating 10 in a press at one end thereof, a metal strap disposed around said stem, a plurality of metal supporting rods carried by said strap and forming a framework extending toward the other end of said bulb, an electrode assembly insulatingly carried by said framework, said electrode assembly comprising a pair of spaced flat insulators threaded over said framework and forming the sole mechanical element of the entire electrode assembly touched by said framework, 15 an anode, means for supporting said anode between said spaced insulators, a grid within said anode, means for supporting said grid between said spaced insulators, a cathode within said grid, means for supporting said cathode between 20 said spaced insulators, leads sealed in said press connected to said cathode, a lead sealed in said stem remote from said press connected to said grid, and a lead sealed in said bulb remote from both press and stem and connected to said anode. 25

5. In an electron discharge device, an evacuated bulb having a reentrant stem terminating in a press at one end thereof, a metal strap disposed around said stem, a plurality of metal supporting rods carried by said strap and forming a 30 framework extending toward the other end of said bulb, an electrode assembly insulatingly supported by said framework and comprising a pair of flat insulators threaded over said framework and forming the sole mechanical connecting medium 35 between said electrode assembly and framework, an anode disposed between said insulators, wires passing through said insulators and anode for maintaining said anode between said insulators, a grid disposed within said anode, leads sealed 40 in said press and connected to the cathode, a lead sealed in said stem remote from said press and connected to said grid, and a lead sealed in said bulb remote from both stem and press and connected to at least one of the anode supporting 45 wires. 50

6. In an electron discharge device, an evacuated bulb having a reentrant stem terminating in a press at each of the opposite ends thereof, a metal strap disposed around one stem, a plurality of metal supporting members carried by said strap and forming a framework extending toward the other stem, an electrode assembly insulatingly supported by said framework and comprising a pair of spaced insulators engaged by 55 said framework and being the only element of said electrode assembly contacted by said framework, an anode between said insulators, a plurality of metal members passing through said insulators and anode and extending toward said other press, a strap around said second stem and connected to said last named wires, a grid electrode disposed within said anode and supported between said insulators, a cathode disposed within said grid and supported between said insulators, means on said framework wires for locking said entire assembly from movement away from said first stem, means on said anode supporting wires for locking said entire assembly from movement 60

away from said second stem, and connections for said cathode grid and anode electrodes.

7. The tube of claim 6 wherein leads sealed in said first press are connected to said cathode, a lead sealed in said first stem remote from said first press is connected to said grid, and wherein a lead sealed in said second press is connected to one of the anode supporting rods.

8. In an electron discharge device, an evacuated bulb having a reentrant stem terminating in a press at one end thereof, a metal strap disposed around said stem, a plurality of metal supporting rods carried by said strap and forming a framework extending toward the other end of said bulb, an electrode assembly insulatingly supported by said framework and comprising a pair of spaced insulators threaded over said framework and forming the only elements of said electrode assembly touched by said framework, an anode between said insulators, wire rods threaded through said insulators and anode for maintaining said anode between said insulators, a grid disposed within said anode and supported between said insulators, a cathode disposed within said grid and supported between said insulators, leads sealed in said press and connected to said cathode, a lead sealed in said stem remote from said press and connected to said grid, a lead

sealed in said bulb remote from said stem and press and connected to one of said anode supporting rods, and means for supporting the electrode assembly end remote from said press and from the bulb end opposite said stem.

9. In an electron discharge device, an evacuated bulb having a reentrant stem terminating in a press at one end thereof, a metal strap disposed around said stem, a plurality of metal supporting members carried by said strap and forming a framework extending toward the other end of said bulb, an electrode assembly insulatingly supported by said framework, said assembly comprising a pair of spaced insulators engaged by said framework members and being the only elements of the entire electrode assembly touched by said framework, an anode supported between said insulators, a grid within said anode and supported between said insulators, a cathode disposed within said grid and supported between said insulators, cathode leads sealed in said press and connected to the cathode terminals, a lead sealed in the stem remote from said press and connected to said grid, and another lead sealed in said bulb remote from both stem and press and connected to said anode.
